The ornamental design for a display screen with a graphical user interface, as shown and described.

DESCRIPTION

FIG. 1 is a front view of a display screen with a graphical user interface showing our new design in a first state;

FIG. 2 is a front view thereof showing our new design in a second state;

FIG. 3 is a front view thereof showing our new design in a third state;

FIG. 4 is a front view thereof showing our new design in a fourth state;

FIG. 5 is a front view thereof showing our new design in a fifth state;

FIG. 6 is a front view thereof showing our new design in a sixth state;

FIG. 7 is a front view thereof showing our new design in a seventh state;

FIG. 8 is a front view thereof showing our new design in a eighth state;

FIG. 9 is a front view thereof showing our new design in a ninth state;

FIG. 10 is a front view thereof showing our new design in a tenth state; and,

FIG. 11 is a front view thereof showing our new design in a eleventh state.

The unshaded regions bounded by broken lines and the linear broken lines shown in the drawings illustrate portions of the display screen with a graphical user interface that forms no part of the claimed design.
